FIG. 5

UNITED STATES PATENT OFFICE

2,264,127

BALL TARGET

Thorstein Arge, Jackson Heights, N. Y.

Application July 13, 1940, Serial No. 345,276

3 Claims. (Cl. 273—102.1)

The present invention relates to an amusement device, and more particularly, to a target game adapted for use with balls and other resilient missiles to be thrown or otherwise projected thereat.

It is an object of the present invention to provide a new amusement device whereby any number of persons can obtain healthful exercise and diversion in the use of said device.

It is another object of this invention to provide a target amusement device for use with balls and other resilient missiles to indicate the accuracy of a player's aim, whereby the skill of the eye and the strength and proficiency of the throwing arm can be appraised and improved.

It is a further object of the invention to provide a novel target amusement device having audible means for indicating a bull's-eye hit thereon.

It is also an object of the invention to incorporate in a ball target game means for retaining the ball when a player fails to hit the target, whereby accidental damage to surrounding objects can be eliminated.

My invention also contemplates the provision of a target amusement device wherein the field is adapted to return to a player balls and other resilient missiles projected thereat.

Furthermore, it is within the contemplation of the invention to provide a novel target amusement device wherein the field is angularly displaceable whereby variations in the distance of a player therefrom can be compensated.

Another object of my invention is to contribute an improved amusement device of variable difficulty adapted for regulation in accordance with variations in skill of the players whereby an amusement device is provided of sufficient simplicity to be enjoyed by the sports dilettante and yet capable of requiring such skill as to challenge the ability of the trained athlete.

My invention further provides a target game of simple and inexpensive construction which can be furnished at low cost for use in homes, athletic and social clubs, amusement parks, carnivals and gymnasia.

Other objects and advantages of my invention will become apparent from the following description taken in conjunction with the accompanying drawings, in which:

Fig. 1 illustrates a side elevational view of my target amusement device;

Fig. 2 is a view of my improved device normal to the plane of the target disc;

Fig. 3 shows a bottom plan view of the target disc element of my improved device;

Fig. 4 depicts a side elevation of said target

disc with the lower part in cross section taken on line 4—4 of Fig. 3; and

Fig. 5 illustrates a floor plan of the playing court to be used in conjunction with my novel amusement device.

Broadly stated, the present invention relates to an amusement device having a target disc mounted upon a frame and having, as the bull's-eye of said target, a plunger adapted for causing an associated bell to sound when the plunger is depressed by a ball or other thrown object. The target disc is pivoted upon the frame and is angularly displaceable thereon, whereby the angle of the target field to the horizontal can be adjusted. It is preferred to affix to the back of the target disc a quadrant having a scale and index for indicating the correct angle at which the disc should be placed to correspond with the distance therefrom of a player. Means are provided for fixing the disc in the adjusted position. I also prefer to employ a net or other retaining device surrounding the disc for the purpose of collecting balls which fail to hit the target.

For the purpose of giving those skilled in the art a better understanding of my invention, the following description of a preferred embodiment is given.

Referring to Figs. 1 and 2, reference character 1 designates a frame having, preferably, a quadrangular base and made of cast iron or other material which can supply a firm, sturdy stand for my device. Frame 1 stands upon legs 2, which are preferably padded to prevent shifting, and upright members at the corners of the base are curved inwardly to come together at the top of the frame. Thus, the front uprights 3 of the frame converge at the top and are joined by a hinge bolt 4. Pivoted between them upon the bolt 4 is a bracket 5 which is attached to the back of a target disc 6. The bracket is provided with a tapped bore 27 adapted to admit a set screw for holding the bolt in place in the bracket.

The target disc 6 is preferably more than a foot in diameter, say about fourteen inches, and it is preferably a die casting or other material which can afford a true, smooth plane surface free from any tendency to warp or crack. At approximately the center of the target disc, a bull's-eye plunger 7 is provided. The bull's-eye is flat-surfaced and preferably of bright metal of the order of about two and one-half inches in diameter, and it protrudes for a slight distance, say about $\frac{1}{2}$ of an inch, above the plane surface of the disc. As will be pointed out in greater detail infra in connection with Figs. 3 and 4, the

bull's-eye plunger is adapted for movement perpendicular to the circular target disc and actuates a hammer 8 which is associated with a bell 9.

A quadrant 10 is affixed to the back of the target disc near the top thereof, and this quadrant has for the center of its arc of curvature the hinge bolt 4. Attached to the quadrant is a scale 11 graduated in numbers corresponding to the distance in yards at which a player should stand from the device for the particular angle of the target disc. The rear uprights 12 of the frame converge upward and forward to come together at the top of the frame and connect with the front uprights. The quadrant is slideably located between the converging rear uprights at the top of the frame and is slotted to accommodate a bolt 28 having a wing nut 13 adapted to fix the quadrant in any desired position with respect to the frame. An index pointer 14 is attached to the frame at the point where the quadrant and scale pass therethrough, and said index pointer is adapted to indicate the graduated figures on the scale to correspond with the angle of the target disc.

An annular edge 15 at the back of the target and preferably integral therewith is pierced with a plurality of perforations, and the strands of a net 16 are attached thereto. The other ends of the strands are attached to a circular rim 17 of somewhat greater diameter than the target disc, say about twenty to about 24 inches, and this rim is supported at a distance of about four to about five inches above the disc by angular brackets 18 which are curved away from the net and around the edge of the target disc and attached to the back thereof by plates 29.

It will be observed that a floor can be provided in the frame 1 to form a cradle for the purpose of storing balls 19 when not in use. It is also preferred to provide two pointers 20 at the middle of the front and back, respectively, of the bottom of the frame to serve as a guide for lining up my amusement device, so that the target squarely faces the player.

Referring now, more particularly, to Figs. 3 and 4, the detailed features of my bell-actuating mechanism will be apparent. The bull's-eye plunger 7 is located in a recess 21 at approximately the center of the target disc 6 and protrudes slightly above the surface of the disc. The recess is slightly deeper than the thickness of the head of the plunger, say about $\frac{1}{2}$ of an inch, so that the plunger has a possible inward movement of about the order of $\frac{1}{8}$ of an inch. The end of the plunger shank passes through a guide 22 behind the disc, and a pin 23 is passed through a hole in the end of the shank and serves as a stop to prevent the plunger from falling forward out of the recess. A light spring 24 is coiled around the shank of the plunger and is compressed between the head of the plunger and the guide 22. The end of the plunger shank is in substantial contact with one arm of a tripper 25, which is mounted on a pin 26. The other and heavier arm of the tripper is in substantial contact with an arm of the bell hammer 8. The bell hammer is in the shape of a bell crank, and its other arm is adapted to tap the bell 9, which is preferably positioned near the bottom of the back of the target disc.

In the operation of my improved amusement device, a player adjusts the movable target disc by loosening the wing nut 13 and sliding the quadrant 10 up or down until the index pointer 14 indicates the figure on scale 11 corresponding

to the distance in yards at which he intends to stand from the target. The wing nut is then securely fastened, and the player takes his position at the predetermined distance. He throws 5 a ball at the target, aiming at the bull's-eye in the approximate center thereof. When the bull's-eye is struck, the plunger 7 is depressed in the recess 21, compressing the spring 24 and moving the tripper 25 about the pin 26. The 10 movement of the tripper in turn actuates the hammer 8, which taps the bell 9, providing an audible indication that a bull's-eye hit has been scored. When the ball rebounds from the bull's-eye head of the plunger, the spring 24 forces the 15 plunger back into its original position. This recovery of the plunger permits the heavier arm of the tripper 25 to fall, returning the tripper to its original position in contact with the end of the plunger shank. Similarly, the hammer 8 also returns by the gravitational force to its original position. Thus, the entire device is ready for operation again.

Whether the ball hits the bull's-eye or any other part of the target disc, the resilience of 20 the ball and the predetermined angle with the horizontal at which the disc has been adjusted combine to return the ball to the hands of the player. It will be apparent that the slight protrusion of the head of the bull's-eye plunger 25 above the surface of the target disc or its slight depression therebelow can have no appreciable effect upon the rebound of the ball. Thus, a 30 device is provided which can be simply adjusted, depending upon the skill of the player, for any distance at which said player may elect to stand, and a ball thrown by him will return to his hands after hitting the target.

The net 16, which is stretched between the 35 annular edge 15 behind the target disc and the rim 17 above the disc, serves as a basket to retain balls which fail to hit the target. The resilience of the balls is spent upon the yielding strands of the net, so that accidental damage to surrounding objects by a bounding ball is eliminated. 40 It will be observed that the preferred mounting for the net which I have provided is clear of the periphery of the target disc, so that the total area of the target is unobstructed.

Various types of healthful, exciting and diverting games can be played with my improved 45 target amusement device. An individual can employ the device for independent practice and amusement. By determining the distance in yards at which he wishes to stand, the player 50 can move the quadrant so that the corresponding number on the scale is opposite the index pointer. In this manner, the angle necessary for the ball to bounce back to him after hitting the target is easily obtained, and it will be observed 55 that such provision for returning the ball to the player at any desired position is a feature of my novel device. At Fig. 5, a floor plan for a court to be used with my device indicates a position Z at which an individual player can 60 stand at a distance about six yards from the target and have the ball returned to him. Similarly, a group of players can successively take this position and compete against each other for an optimum score, as indicated by the sounding 65 of the bell when a bull's-eye hit is made.

By standing at an equal distance from the center line W-Z of the court, two players can play the game in direct opposition to each other. The first player, at point X for example, throws 70 the ball at the target, and his opponent, say

at Y, catches the ball as its bounces from the target and in turn throws it back at the target, from which it rebounds to the first player. In like manner, an experienced player can simulate the conditions of this game by standing first at position X and throwing the ball at the target and then running to position Y to make the catch, and vice versa.

Although the present invention has been described in connection with a preferred embodiment thereof, it will be appreciated that certain variations and modifications can be resorted to, as those skilled in the art will understand. For example, while it is preferred to graduate the scale on the quadrant to correspond with the height of the average adult, it will be recognized that a scale which compensates for the height of children of various ages can be as readily employed. This and other variations and modifications are considered to be within the scope of the present specification and within the purview of the appended claims.

I claim:

1. A target amusement device comprising a frame, a field angularly displaceable upon said frame, a bull's-eye plunger located in said field, a bell associated with said plunger behind said field, means connected with the plunger for tapping the bell when the plunger is depressed, means for quickly returning said plunger and said tapping means to their original positions ready for operation again, means for adjusting the angular position of the field whereby the angle of the field can be regulated to correspond with the distance of a player from the field, a scale associated with said field and graduated in linear units for indicating the adjustment of the angular position to correspond with said distance, and means for fixing the field in such adjusted angular position whereby a ball thrown by a player can be made to ring the bell and return to the hands of the player and whereby a healthful and diverting amusement device of variable difficulty is provided.

2. A target amusement device comprising a frame, a field angularly displaceable upon said frame, a bull's-eye plunger located in said field, a bell associated with said plunger behind said field, means connected with the plunger for

tapping the bell when the plunger is depressed, means for quickly returning said plunger and said tapping means to their original positions ready for operation again, means for adjusting the angular position of the field whereby the angle of the field can be regulated to correspond with the distance of a player from the field, a scale associated with said field and graduated in linear units for indicating the adjustment of

- 5 the angular position of the field whereby the angle of the field can be regulated to correspond with the distance of a player from the field, a scale associated with said field and graduated in linear units for indicating the adjustment of
- 10 the angular position to correspond with said distance, means for fixing the field in such adjusted angular position whereby a ball thrown by a player can be made to ring the bell and return to the hands of the player, and retaining
- 15 means surrounding said field adapted to collect balls which fail to strike the field, thus eliminating accidental damage to surrounding objects, whereby a healthful and diverting amusement device of variable difficulty is provided.
- 20 3. A target amusement device comprising a frame, a field angularly displaceable upon said frame, a bull's-eye plunger located in said field, a bell associated with said plunger behind said field, means connected with the plunger for tapping the bell when the plunger is depressed, resilient means for quickly returning said plunger to its original position, gravity-responsive means for returning said tapping means to its original position ready for operation again, pivot
- 25 30 means for adjusting the angular position of the field whereby the angle of the field can be regulated to correspond with the distance of a player from the field, an arcuate scale behind said field and graduated in linear units, an index
- 35 pointer associated with said frame and said arcuate scale for indicating the adjustment of the angular position of the field to correspond with said distance, frictional means for fixing the field in such adjusted angular position whereby
- 40 40 a ball thrown by a player can be made to ring the bell and return to the hands of the player, and a net surrounding said field adapted to collect balls which fail to strike the field, thus eliminating accidental damage to surrounding
- 45 objects, whereby a healthful and diverting amusement device of variable difficulty is provided.

THORSTEIN ARGE.
